ORTHOPEDIC APPLIANCE

Filed Dec. 22, 1928

Irwin Buckner Inventor

By Herbert E. Smith

Attorney

UNITED STATES PATENT OFFICE

IRWIN BUCKNER, OF SPOKANE, WASHINGTON

ORTHOPEDIC APPLIANCE

Application filed December 22, 1928. Serial No. 327,822.

My present invention relates to improvements in orthopedic appliances designed to correct deformities and other abnormalities of the toes and toe nails, thereby removing 5 cause for pain, relieving soreness, and restoring the previously affected toe and toe nail to their normal conditions. The appliance is especially efficacious in relieving ingrowing toe nails where the lateral edges of 10 the nail have become embedded in the flesh of the adjoining portions of the toe, and for holding the nail in position until the nail can naturally maintain its restored normal position, after which the appliance is of course 15 dispensed with.

In carrying out my invention I utilize means whereby the tension for drawing the opposite edges of the nail to normal position is gradually increased without inflicting undue pain to the wearer of the appliance, and for maintaining the tension devices in proper position to successfully perform their required functions, in restoring the nail to its 25 normal condition.

The invention consists in certain novel combinations and arrangements of parts as will hereinafter be more fully set forth and claimed. In the accompanying drawings I have illustrated one complete example, and a slight modification thereof, of the physical embodiment of my invention wherein the parts are combined and arranged according to the best modes I have thus far devised for 30 the practical application of the principles of my invention.

Figure 1 is a view of a human foot with the appliance of my invention applied to the nail of the first or great toe.

Figure 2 is an enlarged front view of the toe with the device applied to the nail and the tension-tie twisted.

Figure 3 is an enlarged perspective view of the tension lever or link detached from the intermediate tension-tie.

Figure 4 is a top plan view of the device in position on a toe nail. Figure 5 is a perspective view of one of the drawhooks. Figure 6 is an enlarged transverse sectional view 50 of the tension link, and Figure 7 is a per-

spective view of a modified form of drawhook.

In order that the general arrangement and utility of parts may readily be understood I have indicated part of a human foot F, with 55 the toes T and nails N, and it will be understood that the ingrowing edges of the nail N are to be withdrawn from the flesh or skin of the toe and restored to natural position, together with the restoration of the entire nail 60 to its natural arched position.

In actual practice I utilize a pair of complementary clamp-levers as 1 and 2, each of which is fashioned with a draw-hook 3 at one end and an eye 4 at the other end, while an 65 intermediate bend 5 is provided in the clamp lever to form a fulcrum point in contact with the upper face of the toe nail. The hooks are designed to engage about the opposite lateral edges of the nail and also the upper and 70 lower faces of the nail along the edges, while the fulcrum points engage against the upper face of the nail a suitable distance from the edges, leaving the inner ends of the clamp-levers projected away from and above the 75 apex of the arched nail.

The inner adjoining ends of the clamp levers are connected at their eyes by a tension-tie of 6 of suitable material that is flexible and may be twisted, and it will be apparent 80 that the tie tends to pull on the lever-arms of the clamp levers and bear the fulcrum points against the upper face of the nail at opposite sides of the center of the nail, while at the same time the hooks are drawn toward one another to shorten the chord of the arc or arch of the nail. In this manner the ingrowing edges of the nail are withdrawn from the flesh and the correct arch is fashioned in the nail to restore the nail to its normal and 90 natural position.

The tension on the tie is increased at regular intervals, or as is necessary to relieve the abnormality by means of a flat tension link 7 which is fashioned with wedge shaped ends 8 95 so that it may with facility be turned end for end while twisting the tie, and the inner faces of this link are oppositely rounded or convexed, as at 9 to facilitate twisting of the tie and maintaining the latter in its proper 100

twisted position. The tie of course passes through the link and the latter normally lies flat on top of the nail to prevent untwisting of the tie. As the edges of the nail are withdrawn a little at a time from the flesh, the link is turned end for end to increase the tension, and the successive increases in the tension of the tie finally restores the nail to natural position, after which the appliance is of course removed.

10 In Figure 7 I have shown one of a pair of modified clamps indicated as 10, and provided with a hook 11, which at its extremity has a flat face 12 that engages under the nail near its edge, and in some instances these hooks may be substituted for the clamp-levers 1 and 2.

Having thus fully described my invention, what I claim as new and desire to secure by Letters Patent is:

- 20 1. An orthopedic appliance comprising a pair of angular clamp levers each having an end hook and an intermediate fulcrum point, said levers having eyes at their adjoining ends and a flexible tension tie connecting said eyes, and a tension link on the tie, whereby the link may be turned to vary the tension of the tie.
- 25 2. An orthopedic appliance comprising a pair of angular clamp levers each having an end hook and an intermediate bend forming a fulcrum point, said levers having eyes and a flexible tension tie connecting the eyes, and a tension link on the tie having interior, oppositely convexed faces for use in varying the tension of the tie.
- 30 35 In testimony whereof I affix my signature.
IRWIN BUCKNER.
